UNITED STATES PATENT OFFICE.

NEWTON M. ANDERSON, OF WORTHINGTON, INDIANA, ASSIGNOR, BY MESNE ASSIGNMENTS, TO THOMAS BEMIS, SR., THOMAS BEMIS, JR., AND RUTH BEMIS, TRUSTEES OF ANDERSON STEAM VULCANIZER COMPANY, A REAL TRUST.

VULCANIZER.

1,359,562.

Specification of Letters Patent. Patented Nov. 23, 1920.

Application filed August 20, 1917. Serial No. 187,122.

To all whom it may concern:

Be it known that I, NEWTON M. ANDERSON, a citizen of the United States, and a resident of Worthington, county of Greene, and State of Indiana, have invented a certain new and useful Vulcanizer; and I do hereby declare that the following is a full, clear, and exact description thereof, reference being had to the accompanying drawings, in which like letters refer to like parts.

The object of this invention is to improve the construction and operation of means for vulcanizing rubber tires and the like.

One feature of the invention is the arrangement to provide for a constant circuit or return of the condensation water. The returning condensation water enters the boiler at a point above the water level. The heating means is arranged so as to heat the boiler above the water level, and also to heat the return condensation water pipe.

In connection with the foregoing, there is a further feature of the invention consisting in means for charging the boiler with water, without reducing the steam pressure therein or in any manner interfering with the operation of the apparatus. This consists of an initial water charging chamber which is in communication with a steam boiler and is shut off therefrom by a valve. When it is desired to charge the boiler, said valve is closed, said water chamber filled and its inlet closed, and then said valve is opened so that the water therefrom will flow into the boiler and without interfering with the steam pressure of the boiler or the operation of the apparatus.

Another feature of the invention consists in the molds being provided with a deflecting partition chamber with a V-shaped projection toward the steam inlet whereby the steam is distributed in opposite directions to said inlets and through the ends of the mold and then to the back of the mold. This promotes the general steam distribution throughout the surface of the mold and in addition to this, to the ends and back thereof, whereby the same will be heated uniformly.

Another feature of the invention consists in means for holding the sand bag in place in the tire while it is being vulcanized.

The full nature of the invention will be understood from the accompanying draw-

ings and the following description and claims.

Figure 1 is a side elevation of the apparatus with a certain portion in central vertical transverse section, as shown. Fig. 2 is a plan view of the apparatus. Fig. 3 is a side elevation of one of the molds at the right hand side of the apparatus as seen in Fig. 1, said mold being shown partially in central vertical longitudinal sections. Fig. 4 is a transverse section of the mold on the line 4-4 of Fig. 3. Fig. 5 is a side elevation of the left hand mold shown in Fig. 1, with a portion thereof in central vertical longitudinal section. Fig. 6 is a plan view of said mold. Fig. 7 is a section on the line 7-7 of Fig. 6, transversely of the mold.

The framework of the apparatus consists of an upper rectangular portion 10 mounted on vertical legs 11 which are braced by a rectangularly disposed brace bar 12 intermediate therein. Centrally located within said frame there is a furnace casing 13 vertically disposed with a steam boiler 14 centrally located therein and spaced therefrom as shown in Fig. 1. At the lower end of the furnace casing and below the boiler there is a gasolene burner 15 supplied with gasolene from the tank 16 through the pipe 17 which is suitably controlled by a valve. A gas burner, either artificial or other gas, an oil burner or other kind of burner can be used. Secured to the water boiler 14 there is a water gage 18.

The molds 20 and 21 are secured to the upper part of the frame at the side thereof. Two of these molds are shown but there may be molds on the other two sides of the frame. The mold 20 has a flat surface, while the mold 21 is segmental, but the form of the molds may be such as desired for the work to be done.

Each mold has a steam chamber 22 therein supplied with steam from the steam boiler passing through the horizontal steam pipe 100 24 central with the steam chamber in the mold. As the steam enters the steam chamber it is distributed to the right hand and to the left, or, in other words, to the ends of the mold preferably by a V-shaped projection 25 on the middle portion of a partition or baffle plate 26 located centrally within the mold. This baffle plate extends from

the top to the bottom of the mold and almost to the ends of the mold, leaving, however, 5 passes 27 at the ends of the mold to permit the steam to pass to the rear of the baffle plate and heat the rear wall of the mold. This promotes the distribution of the steam in the steam chamber, and its further distribution is promoted by the petcocks 28 located at the ends of the molds through 10 which any accumulated air may be removed from the mold, while starting to heat the mold. The condensation water from the mold returns preferably from the central part of the rear portion of the steam chamber, behind the baffle plate 26, to the steam boiler through the return pipe 30, as shown in Fig. 1. This pipe enters the steam boiler below the top of the water gage 18 and above the desired water level within the apparatus boiler. The arrangement is such, 15 that the flame from the burner will pass up through the burner casing 13 around the boiler to a point above the water level and above the pipe 30 so as to superheat the steam and also to superheat the condensation water as it flows from the mold to the boiler just before it enters the boiler, above the water level. In work of this kind the temperature should be about 307 degrees 20 Fahrenheit and, therefore, it is necessary to superheat the steam to a higher temperature than the mere boiling temperature.

For the purpose of charging the steam boiler with water and to do so without interfering with the operation of the apparatus, 25 there is a water supply chamber 35 at the top of the apparatus in communication with the steam boiler by pipes 36 and 37, said pipes or communication being closed or controlled by a valve 38. Water is introduced into said chamber 35 through an opening in the top which is closed by a plug cap 39. When it is desired to introduce more water into the steam boiler, the valve 38 is closed, 40 the cap 39 removed, the chamber 35 filled with water while the top is open to the atmosphere, the cap 39 replaced, and the valve 38 opened. Thus while the water is being introduced, communication with the steam boiler and also the pipe 24 is closed by the valve 38. After the water has been introduced into chamber 35 and cap 39 replaced, then the valve 38 is opened and the water will then descend by gravity into the 45 boiler 14.

In operation of the apparatus a sand bag 49 is employed for vulcanizing the work done on the inner surface of the outer casing 41 for pneumatic tires, as shown in 50 Figs. 3 and 4, also for conforming to the various thicknesses and shapes of the casing to force same to the walls of the mold. The sand bag is placed in the mold at the time of lighting the burner, and by the time 55 the steam is at the proper pressure, usually

60 pounds, it has attained a vulcanizing heat of practically the same temperature as the mold, which causes the work done on the inside of the casing to be vulcanized in place, while the mold vulcanizes the work 70 done on the outside of the casing. The sand bag is oblong and substantially circular intermediate its ends, and is pressed into the shape shown in Fig. 4 by the blocks 42, set-screw 43, clevis 44, and rod 45 at the lower 75 end of the clevis. This clevis is, therefore, removable as the rod 45 is removable from the clevis 44 and then the clevis can be removed from the mold. The lower surface of these clamping blocks 42 is preferably 80 convex in cross section as shown in Fig. 4, for the purpose of pressing out the right and left hand portions of the sand bag against the inner wall of the outer casing. This increases the surface of the sand bag 85 which is in contact with the tire and also causes it to extend up to a higher point against the tire.

It will thus be seen, that the foregoing apparatus is simple in construction, can be 90 easily manipulated and will be efficient in operation. The condensation water will be returned to the steam boiler and the steam boiler in a novel manner can be recharged with water without stopping the apparatus 95 in any way, or interfering with the boiler. The steam is well distributed in the mold and by placing the petcock at a point preferably to the rear of the baffle plate 26 the air accumulating at the end of the mold 100 can be then removed. There are extensions or flanges 46 at the ends of the molds as shown in Fig. 3, which are cooled by the air and, therefore, prevent the mold from making an offset surface on the rubber tire. 105

The invention claimed is:

1. A vulcanizing apparatus including a steam boiler having a heating chamber in the upper portion thereof, means for confining a heating medium around said boiler 110 and the heating chamber therein, a mold having a steam chamber therein, a communication between the steam boiler and the chamber in said mold for supplying the latter with steam, and a return pipe leading 115 from the steam chamber in the mold to the steam boiler.

2. A vulcanizing apparatus including a steam boiler having a heating chamber in the upper portion thereof, a casing surrounding said boiler including said heating chamber and spaced from the boiler, means for conveying heat through the space between said boiler and casing, a mold having a steam chamber therein, a communication 125 between the steam boiler and the chamber in said mold for supplying the latter with steam and a return pipe leading from the steam chamber in the mold to the steam boiler. 130

3. A vulcanizing apparatus including a steam boiler having a heating chamber in the upper portion thereof, means for confining a heating medium around said boiler and the heating chamber therein, a mold having a steam chamber therein, a communication between the steam boiler and the chamber in said mold for supplying the latter with steam, and a return pipe leading from the steam chamber in the mold to the steam boiler, said pipe passing through the heating medium before entering said boiler. 65
- 5 4. A vulcanizing apparatus including a steam boiler having a heating chamber in the upper portion thereof, a casing surrounding said boiler including said heating chamber and spaced from the boiler, means for conveying heat through the space between said boiler and casing, a mold having a steam chamber therein, a communication between the steam boiler and the chamber in said mold for supplying the latter with steam, and a return pipe leading from the steam chamber in the mold to the heating chamber in the boiler above the water level 70 therein. 75
- 10 5. Vulcanizing apparatus including a steam boiler, a mold having a steam chamber therein, a communication between the steam boiler and the chamber in the mold for supplying the latter with steam, a return pipe leading from the steam chamber in the mold to the steam boiler at a point below the top thereof and above the normal water level therein, for returning the condensation water and a heater for the steam boiler in position to heat the return pipe whereby the condensation water is heated before it enters the boiler. 80
- 15 40 6. Vulcanizing apparatus including a steam boiler, a mold having a steam chamber therein, a communication between the steam boiler and the chamber in the mold for supplying the latter with steam, a return pipe leading from the steam chamber in the mold to the steam boiler at a point below the top thereof and above the normal water level therein for returning the condensation water, and a heater for the steam boiler in position for the heated gases therefrom to heat the return pipe and the boiler above the water level. 85
- 20 45 50 7. Vulcanizing apparatus including a mold having a steam chamber therein, means for introducing steam into said chamber at one side of the mold, and a baffle plate longitudinally of said mold with a passageway at each end thereof for deflecting the steam to the ends of the mold and to the portion of said chamber behind the baffle plate. 90
- 25 55 60 8. Vulcanizing apparatus including a mold having a steam chamber therein, means for introducing steam into said chamber at one side of the middle of the mold, and a baffle plate longitudinally of said mold with a passageway at each end thereof, said plate having a V-shaped rib opposite the steam inlet for deflecting the steam to the ends of the mold and to the portion of the chamber 95 behind the baffle plate. 100
- 30 5 9. Vulcanizing apparatus including a steam boiler, a mold having a steam chamber therein, a pipe leading from the boiler to the steam chamber, a baffle plate extending longitudinally of the steam chamber with a pass at each end thereof for deflecting the steam to the ends of the mold and into the chamber to the rear of the baffle plate, and a return pipe leading from the chamber at the rear of the baffle plate back to the steam boiler. 105
- 35 10. Vulcanizing apparatus including a steam boiler, a mold having a steam chamber therein, a pipe leading from the upper part of the boiler to the middle of the steam chamber, a baffle plate extending longitudinally of the steam chamber with a pass at each end thereof for deflecting the steam to the ends of the mold and into the chamber 110 to the rear of the baffle plate, a return pipe leading from the chamber back to the rear of the baffle plate, back to the steam boiler below the upper end thereof, and a petcock at each end of the chamber. 115
- 40 11. Vulcanizing apparatus including a mold with a steam chamber therein, a steam boiler, a pipe leading from the steam boiler to the steam chamber in said mold, a pipe extending up from said steam pipe, a water receiving chamber connected to said pipe, a valve in said pipe, and means for closing the water receiving chamber, substantially as and for the purpose set forth. 120
- 45 12. A vulcanizing apparatus, including a mold with a steam chamber therein, a steam boiler connected with the steam chamber of said mold, a water receiving chamber communicating with said boiler and having an opening to the atmosphere, a valve for closing the communication between the boiler and water receiving chamber while the water receiving chamber is being filled, and means for closing said opening in said water receiving chamber after the chamber has been filled to prevent the escape of water and steam therefrom after said valve has been opened and to enable the steam pressure of the boiler and gravity to control the passage of water from the receiving chamber to the boiler. 125

In witness whereof, I have hereunto affixed my signature.

NEWTON M. ANDERSON.
